S. Baldwin.
Carding Mach.

N° 19,011.

Patented Jan. 5, 1858.

UNITED STATES PATENT OFFICE.

S. BALDWIN, OF ST. LOUIS, MISSOURI.

SPINNING OAKUM.

Specification of Letters Patent No. 19,011, dated January 5, 1858.

To all whom it may concern:

Be it known that I, SMITH BALDWIN, of St. Louis, in the county of St. Louis and State of Missouri, have invented a new and useful Machine for Spinning Oakum; and I do hereby declare that the following is a full, clear, and exact description of the same, reference being had to the accompanying drawings, making part of this specification, in which—

Figure 1, is a longitudinal vertical section of the machine. Fig. 2, is a plan of the same. Fig. 3, is a transverse section of the same in the line *x, x*, of Fig. 1, looking in the direction of the arrow shown near the said line.

Similar letters of reference indicate corresponding parts in the several figures.

This machine combines the processes of carding and spinning, and the picked oakum being supplied to it, is converted into a merchantable state for the use of calkers, &c., at one continuous operation.

To enable others to make and use my machine, I will proceed to describe its construction and operation.

The portion of the machine seen at the right hand end of Figs. 1 and 2, is substantially like a common carding machine, except that a different device is employed to take the web of carded material from the "doffer," and a device is added for the purpose of removing from the teeth of the "doffer" any tarry burs or knobs that may collect among the teeth, and that would interfere with the proper operation.

A, is the feed apron; and B, the platform on which the person stands to supply the picked material thereto.

40 C, C, are the feed rollers.

D, is the main cylinder.

E, F, G, are workers and strippers.

H, is a "fancy" cylinder; and I, is the "doffer."

45 J, J, are two series of revolving blades for taking the web from the "doffer," attached to separate shafts arranged parallel with the doffer; the blades on one shaft being arranged midway between those on the

50 other shaft, and the shafts rotating in opposite directions; so that the blades of the two shafts take the carded web between them, and pull it from the doffer, as shown in Fig.

1 where the oakum is shown in red color.

55 The blades J, J, instead of having serrated edges like the combs commonly employed to

take the carded material from the doffer of the common carding engines, have straight edges as shown in Fig. 2; as I find by experiment that the serrated comb edge is not adapted for removing the oakum without breaking the web, while the revolving straight-edged blades do it most effectually. The device for removing from the doffer the tarry burs or knobs, consists of a series of toothed or serrated blades *a, a*, attached to a shaft M, that rotates in the direction of the arrows, the teeth of the said blades operating upon the upper part of the doffer to pick out the burs or knobs that remain among the teeth after the web has been removed from the doffer.

O, is an endless apron, arranged in a nearly horizontal position, below the carding machinery, upon two rollers *c, c¹*, and extending beyond both ends thereof, and having its upper surface moving in the direction of the arrow shown near N. N, is another endless apron running on two rollers 6, 6, placed under the combs J, J, and inclining 80 outward from the machine toward the bottom, which is nearly close to the apron O. The outer surface of this apron N, has a descending motion and receives the web of carded material as it is delivered from the doffer by the revolving blades J, J, to convey it without breakage to the apron O, which, moving in the direction indicated, carries the web backward under the carding machinery toward the spinning or twisting 90 devices at the left hand end of the machine. The arrangement and direction of the motion of this apron O, serve or are such as to receive all the short fibers which fall from the carding material, to be incorporated with 95 the longer fibers in the spinning process, and hence to effect a considerable saving of otherwise worthless material.

P, P, are two stationary funnel-shaped conductors at the left-hand end of the apron 100 O, which divide the web into two slivers, and condense it slightly as it leaves the said apron to be conveyed to the revolving roving tubes Q, Q, by which the required twist is imparted to it.

d, is a pressure roller arranged above the roller *c¹*, of the apron O, to effect a further condensation of the slivers as they leave the conductors P, P.

S, is a roller placed close above the apron 110 O, at the edge of the stationary apron e, that is attached to the conductors P, P, said

roller rotating in the direction of the arrow shown near it, to prevent the web from passing under the said apron *e*, and to convey it to the said apron *e*, and conductors *P*, *P*. 5 *f f*, are grooved drawing and condensing rollers, to draw the material slightly in its passage through the roving tubes and further condense it. 10 *g g*, are two funnel shaped conductors to receive the rovings from the drawing rollers *f f*, and lead them to the rollers *h h*, upon which it is wound for the formation of hanks of proper size for the use of calkers or others; said conductors being attached to a 15 sliding bar *i*, and having a lateral transverse motion to cause the roving to be laid evenly upon the rollers *h h*, which are intended to have proper mechanism applied to throw them out of the machine, to give

place to an empty pair when a sufficient quantity for a hank is wound upon them.

What I claim as my invention and desire to secure by Letters Patent, is—

1. The employment of two series of revolving straight or knife-edged combs *J J*, 25 arranged and operating as described for the purpose of taking the web of carded oakum in an unbroken sheet from the doffer.

2. The employment in combination with the said endless moving apron *O*, and the stationary apron *e*, belonging to the first conductors *P P*, of the roller *S*, operating as and for the purpose specified.

SMITH BALDWIN.
